UNITED STATES PATENT OFFICE.

DANIEL HUSSEY, OF NASHUA, NEW HAMPSHIRE.

IMPROVEMENT IN LET-OFFS FOR LOOMS.

Specification forming part of Letters Patent No. 59,024, dated October 23, 1866.

To all whom it may concern:

Be it known that I, DANIEL HUSSEY, of Nashua, in the county of Hillsborough and State of New Hampshire, have invented a new and useful or Improved Let-Off Mechanism for Looms; and I do hereby declare the same to be fully described in the following specification and represented in the accompanying drawings, of which—

Figure 1 is a top view; Fig. 2 a side elevation, and Fig. 3 a rear elevation, of my said invention as applied to the yarn-beam and guide of a loom.

In carrying out such invention I combine with what is usually termed an "escapement let-off mechanism" a mechanism (positive in its action) whereby the slack of the warps during the process of crossing them, or moving their harnesses, is taken up.

It has been found that the usual spring or weight applied to the warp-guide or whip-roller (such an application of a weight being represented in the specification of Silas Shepard's patent, Reissue No. 1,507 of United States patents) is not, in my opinion, sufficient to be relied on for maintaining the requisite tension on the warps while their harnesses are in movement. I have therefore applied to the warp-guide and the escapement mechanism a mechanism which will not only positively perform the function of maintaining the warps at a proper tension while their harnesses are being moved, but will operate to firmly support the warp-guide while the filling is in the act of being beaten up by the lay. Besides performing these effects, the invention will allow the warp-guide to be depressed far enough to enable the impelling-pawl (to be hereinafter described) to work the detent of the escapement at the proper period for such to take place.

In the drawings, A denotes the frame of a loom; B, the warp-beam or roller; C, the warp-guide; D, the breast-beam; E, the bell-cranned shaft for operating the lay, the two lay-cranks of such shaft being exhibited at b b.

The shaft of the warp-beam B, by means of a train of gears, c d e f, engages with an escapement-wheel, g, provided with a detent, F, having two pallets, h i, and a projection, k, formed and arranged as exhibited in Fig. 2. The said detent is placed directly over the es-

capement-wheel, and is supported by a pin, l, projecting from the loom-frame. The detent should be capable of being freely turned on the pin.

An impelling-pawl, m, carried by a crank-pin, n, arranged eccentrically to the axis of the shaft, and projected from the side of a cam, o, affixed upon such shaft, is for operating the detent. This pawl is supported in a fork, p, extending down from an arm, r, which projects from one of the journals of the warp-guide C, and directly over the periphery of the said cam o.

The arm r rests upon the upper end of a rod, s, which is to be capable of moving vertically in guides t t, projecting from the loom-frame, and in turn is supported by a helical spring, u, which encompasses the rod and rests on the lowermost of the guides. A nut, v, screwed on the rod s, rests on the upper end of the spring, and by such spring is borne up against the upper of the guides t t.

The cam o is to be so formed that during its revolution, by its action against and with reference to the arm r, it will cause the following to take place—that is to say, first, the said arm to be raised sufficiently to maintain the proper tension on the warps while their harnesses are in movement; second, the said arm to rest on and be supported by the cam at the period when the lay is beating the filling close into the warps; third, to allow the arm to descend and depress the pawl far enough for it to put in motion the detent or the escapement.

Whenever it may be desirable for the warp-beam to turn and deliver yarn while the operation of weaving cloth is being carried on by the loom, the strain of the warp on the warp-guide will induce a depression of the arm r sufficient to cause the pawl to move the detent of the escapement-wheel. Such a movement of the detent will be accompanied by a rotary movement of the yarn-beam, whereby yarn will be delivered therefrom.

The cam may be constructed so that while it will not perform the function of supporting the arm of the yarn-guide while the filling is being beaten into the warps, it will perform the other functions, as above explained. In firmly supporting the yarn-guide while the filling is in the act of being beaten into the cloth,

the escapement mechanism provided with the said cam, and otherwise constructed as explained, except in that feature of the cam by which it is caused to raise the arm during the period of movement of the harnesses, is analogous to the invention patented by George Draper, and described in the United States Patent No. 39,469, granted August 11, 1863.

What I claim as my invention is—

The combination of the cam *o* and the im-

pelling-pawl *m*, applied to the cranked shaft, as described, with the arm *r* and the escapement mechanism applied to the yarn-guide and the yarn-beam, the whole being to operate in manner and under circumstances substantially as set forth.

DANIEL HUSSEY.
